W. PRESCOTT.
RAILROAD DITCHER.

No. 442,457.

Patented Dec. 9, 1890.

UNITED STATES PATENT OFFICE.

WILLIAM PRESCOTT, OF FORT MADISON, IOWA.

RAILROAD-DITCHER.

SPECIFICATION forming part of Letters Patent No. 442,457, dated December 9, 1890.

Application filed April 15, 1890. Serial No. 348,007. (No model.)

To all whom it may concern:

Be it known that I, WILLIAM PRESCOTT, a citizen of the United States, residing at Fort Madison, Lee county, Iowa, have invented a new and useful Improvement in Railroad-Ditchers, of which the following is a specification.

The object of this invention is to construct an efficient and easily-operated ditcher capable, among other things, of being adjusted to different widths of road and to different heights, and adapted when not in use to be swung around, so as to occupy little, if any, more space than the width of the car on which it is mounted; and the invention consists in the features and details of construction hereinafter described and claimed.

In the drawings, Figure 1 is a side elevation of my improved ditcher with the parts in position for transportation; Fig. 2, a plan view thereof with the parts in position for working; Fig. 3, a side elevation of a portion of the ditcher, showing one of the scoops and the derrick for carrying the same; and Figs. 4, 5, and 6, detail views of the adjusting mechanism.

A is the car on which the ditcher is mounted; B, the horizontal frame-work of the ditcher; B', a turn-table; B'', a vertical frame-work attached to the frame B; C C, the excavating buckets or scoops; C', the arms supporting the same; D D, the derricks in which the scoops are supported and operated; d', blocks in which the upper ends of the derricks are pivoted; D'', similar blocks in which the lower ends of the derricks are pivoted; E, a shaft supported in suitable bearings e upon the frame-work; E', drums on such shaft; F, ropes attached to the buckets and adapted to be wound upon the drums; G, a belt passing over the axle of the car; H, a clutch; H', a brake; I I I I, hooks engaging with the frame-work B; I' I' I' I', latches engaging with such hooks; J, rods attached to the derricks D and hooking into a block j' on a rod J'; K K and K' K', braces, and L L shovels.

The flat car A, which supports the ditcher, is made in the ordinary well-known manner, and, since its construction will be obvious from an inspection of the drawings, requires no further description. To this car is at-

tached the turn-table B', consisting of an iron ring with a central boss upon which the frame of the ditcher rests. The frame B is constructed, preferably, of heavy timbers, and 55 substantially in the form shown in the drawings, consisting of two longitudinal timbers joined by five cross-timbers. It is supported, as above stated, upon a turn-table to allow it to be swung around, as hereinafter set forth. 60 At each end of this frame and at a point near the end thereof stands a vertical frame B'', consisting of two timbers fastened to the frame B and joined at the upper ends by a block or plate D', preferably of metal. The 65 derricks D are also preferably made of wood and substantially in the form shown. They are pivoted at their upper ends in blocks d' and at their lower ends in blocks or boxes D''. The block d' is dovetailed into the block 70 D', and a screw passes through a lug on such block and is fastened to block d', so that as it is revolved in one direction or the other the block d' will be moved sidewise, carrying with it the upper end of the derrick pivoted thereon. In like manner the blocks D'' are slid 75 back and forth upon the front timber of the frame B by means of suitable screws passing through lugs d''. In this manner the derricks can be adjusted at various distances from the 80 sides of the car, thus enabling the scoops to operate at different points and excavate a greater or less width of road. The scoops or buckets C are made in the ordinary form, and are provided with automatically - locking 85 hinged bottoms c, to which are attached ropes c' for the purpose of unfastening them when it is desired to discharge the contents of the scoops. The scoops are fastened at a point near their middle to arms C', extending about 90 at right angles to the scoops. Each arm is pivoted at its other end between two plates secured to the vertical timbers of the derrick. These plates are provided, as shown, with a number of holes, so that the scoops can be adjusted at different heights, ropes and pulleys 95 N being provided for the purpose of raising the arms.

A shaft E is journaled in suitable bearings on the frame B, and at either end thereof at a 100 point behind the derricks is attached a winding-drum E'. Chains or ropes F are attached

to the bails of the buckets, and, passing over pulleys on the derricks and frames B'', are attached to these drums. On this shaft is mounted a loose pulley of the well-known form, 5 and a belt G (shown in dotted lines in Fig. 1) runs over this pulley and over a drum upon one of the axles of the car from whence the operating power is derived. A suitable clutch II is rigidly secured to the shaft, moved by 10 means of a lever h. If desired, this clutch and loose pulley may be situated on the axle of the car and operated by a lever extending up through the car-floor or other suitable means. In this case the belt will pass over 15 an ordinary pulley fixed to the shaft E. I also prefer to provide a brake II' for this shaft, consisting of a strip of metal partially embracing a disk fixed to the shaft and tightened on such disk by means of a hand-lever 20 h', mounted on the frame of the machine.

To hold the frame B in its working position across the car, hooks I are provided, adapted to engage, as shown in Fig. 2, with this frame. To lock these hooks, I provide latches I', 25 which swing down behind the hooks and keep them from unfastening. The timbers K, extending from suitable sockets on the car to the corners of the frame B, act as braces to strengthen such frame and aid it to stand the 30 strain to which it is subjected. Braces K'K' serve to take the strain that would otherwise come upon the scoops. Levers k' are used to raise these braces out of the way when the frame B is rotated upon the turn-table.

35 At each side of the car, preferably at a point near the forward trucks, is attached a shovel L, which serves to push away any dirt falling too near the track. The shovels are carried upon vertical bars l, that slide between two uprights attached to the car, and can be adjusted to various heights by means of pins l', passing through the bars l and resting on the tops of the uprights. A hose may be provided to wash out the scoops, if desired.

45 The mode of operation is as follows: The clutch being in engagement with the loose pulley, as the car is moved the shaft and drums are revolved, winding up the chains and raising the buckets. When these are 50 raised as high as desired, the clutch is thrown out and the buckets held by means of the brake. On reaching the point where the ditching is to be done the brake is released and the scoops fall by their own weight, the

55 speed at which they fall being regulated by the brake. The buckets then stand, as shown in Fig. 3, nearly horizontal, but with a slight forward dip or inclination. The car is then moved forward until the scoops are filled, 60 when the clutch is again thrown in and the scoops raised and held by the brake as the car passes to the dumping-place, when the bottoms of the scoops are unlocked by pulling on the ropes c', and, falling, discharge the 65 contents of the scoops. The car then moves forward to fill the scoops, and they are filled, raised, and discharged, as before. When it

is desired to swing the frame B on the car, the latches are raised, the hooks thrown back, and the braces K'K' removed, and the ditcher 70 is then swung on the turn-table into line with the car. The rods J are then unhooked from the block j' and the derricks also swung into line with the car. In this position, which is shown in Fig. 1, the ditcher takes little, if 75 any, more room than the car itself, so that it can pass through bridges, tunnels, and narrow points on the road without having to be taken apart for such purpose.

Any other manner of connecting the framework to the car that will allow it to swing around thereon may be employed instead of a turn-table, if desired.

I claim—

1. In a railroad-ditcher, the combination of 85 the car A, frame B, rotatably mounted thereon, frames B'', attached to frame B, derricks D, mounted in such frames, and scoops pivotally supported in such derricks, substantially as described.

2. In a railroad-ditcher, the combination of 90 a car A, frame B, pivotally mounted thereon, hooks I, and latches I', whereby the frame is held in position for working, substantially as described.

3. In a railroad-ditcher, the combination of 95 the frames B and B'', a derrick D, mounted therein, and means for securing the sidewise adjustment of such derrick, substantially as described.

4. In a railroad-ditcher, the combination of 100 the car A, frames B B'', sliding blocks d' D'', scoop - carrying derricks pivoted in such blocks, and means for moving such blocks back and forth, whereby the derricks and 105 scoops are adjusted sidewise, substantially as described.

5. In a railroad-ditcher, the combination of 110 frames B and B'', derricks D, mounted thereon, scoops C, pivoted in such derricks, a shaft E, journaled in frame B, carrying winding-drums E', and ropes or chains attached to the 115 scoops, whereby as the shaft is revolved the scoops are raised, substantially as described.

6. In a railroad-ditcher, the combination of 120 derricks D, scoops C, supported therein, and vertically-adjustable braces K', secured to the machine and extending to and engaging with the back of the scoops to receive the strain when the scoops are in use, substantially as 125 described.

7. In a railroad-ditcher, the combination of 130 the car A, frames B and B'', derricks mounted therein, scoops pivotally supported in such derricks, a shaft E, journaled in frame B and carrying drums E', ropes leading from the scoops to such drums, and means whereby the revolution of the car-axle revolves the shaft to raise the scoops, substantially as described.

8. In a railroad-ditcher, the combination of 135 a car A, frame B, shaft E, carrying drums E', means whereby the revolution of the car-axle revolves the shaft E, and a brake II' for regu-

lating the speed of such shaft, substantially as described.

9. In a railroad-ditcher, the combination of frames B and B'', derricks D, rod J', block j', and rods J, attached to such derricks and engaging with the block j', whereby the derricks are held in place, substantially as described.

10. In a railroad-ditcher, the combination of a car, ditcher frame-work rotatively supported thereon, scoops pivotally supported on such frame-work, a shaft journaled therein and connected with the scoops, and a driving-belt leading from the car-axle to such shaft, whereby the revolution of the axle revolves

the shaft and raises the scoops, substantially as described.

11. In a railroad-ditcher, the combination of a derrick D, provided with perforated plates M, an arm C' carrying a scoop C, and a suitable pin adapted to pass through the perforations in the plate M and a hole in the end of the arm C', whereby the end of such arm may be vertically adjusted, substantially as described. 20
